UNITED STATES PATENT OFFICE.

JULIA A. ST. CLAIR, OF SAN ANTONIO, TEXAS.

FASTENER FOR BUTTONS, ETC.

Application filed June 23, 1922. Serial No. 571,390.

To all whom it may concern:

Be it known that I, JULIA A. ST. CLAIR, citizen of the United States of America, residing at San Antonio, in the county of Bexar and State of Texas, have invented certain new and useful Improvements in Fasteners for Buttons, Etc., of which the following is a full, clear, and exact description.

10 This invention relates to fasteners for buttons, and the like.

An important feature of the invention comprises a device for securing buttons and like articles, of the type that are secured in position on cloth, leather, etc., by a wire staple so that the prongs of the staple are firmly anchored in position upon the inside of the fabric, and are covered by a protecting element. The protecting element is of such a nature as to completely conceal, as well as to secure in position, the ends of the staple. Rubbing of other garments against the staple ends and other injurious results will be thereby avoided by my invention.

25 The above and other important features of the invention will be better understood from the following description, in connection with the accompanying drawings, and the novel features of the invention will be 30 pointed out in the appended claims.

In the drawings:

Fig. 1 represents the invention in plan view;

Fig. 2 illustrates the fastening device with 35 the parts opened;

Fig. 3 is a section on the line 3—3, Fig. 1;

Fig. 4 is a section on the line 4—4, Fig. 1;

Fig. 5 is a side elevation of a staple end bending tool;

40 Fig. 6 is a section on the line 6—6, Fig. 5; and

Fig. 7 is a plan view of the tool shown in Fig. 5.

The invention comprises two members 5, 45 6 which are adapted to clamp and enclose between them the ends of the staple which secures the button or other device to the fabric or goods.

Referring particularly to Fig. 2, the member 5, which may be constructed of sheet metal and of substantially the form shown, has its edge slightly turned or rolled, as shown at 10. Within this rolled edge is a wire or strand 7, having certain portions 55 exposed by the slightly indented or recessed portions 20, the wire preferably being pro-

vided with a loop 8 so that it may be resiliently seated in the groove formed by the turned over edge 10.

The cover or top member of the fastening device is provided with a rolled extension 9, which encloses the wire 7 opposite one of the recesses 20, thereby hinging the part 6 to part 5.

Immediately opposite the hinge 9, the part 6 is provided with a bent over snap fastener 11, which when the part 6 is folded over upon the part 5, will snap over the wire 7 opposite the other recess 20, thereby securing the members together in closed position as illustrated in Figs. 3 and 4.

The part 5 of the fastener is provided with two holes 12, 12 suitably spaced apart, and said part 5 is also provided with two struck-up tongues or keepers 14, 14 which are spaced beyond the holes 12, as illustrated in Fig. 2. These tongues are for the purpose of retaining in bent over position the ends of the staple.

Referring to Fig. 3, a button, or similar device 1, is provided with the usual openings through which thread or other fastening means is passed for securing the button to a garment, or the like. A staple 3 made of any suitable gage of wire, has its two limbs passed through the openings in the button, thence through the cloth of the garment, fabric, or the like, and thence through similar openings in a washer 21, which lies on the opposite side of the cloth from that occupied by the button. The limbs of the staple are then passed through the openings 12 of the fastener member 5. The tool 16, which may comprise a piece of metal bent along a longitudinal line, as shown, so as to form in cross section a V, is provided with a hole 18. In the use of this tool, the same is guided along one of the staple ends 3^a or 3^b, until such end projects through the hole 18. The tool 16 is then turned which bends the staple end over at right angles so that the end will lie flat on the inner face of the member 5, said end then being placed beneath a tongue 14. The other end of the member is then bent over in the same manner and its end passed beneath the other tongue 14. The part 6 of the fastener is then closed over the part 5, the curved tongue 11 snapping over the wire 7, thus securing the two members together in their normal relation.

It will be seen that the ends of the staple

will be securely maintained by the tongues 14 on the face of the fastener member 5, and that when the part 6 is secured over the part 5 the staple ends will be protected and concealed and all danger of other portions of the garment catching in these ends will be prevented, as a smooth surface will be presented by the part 6 which, together with the part 5, completely encloses the staple 10 ends.

If desired, the member 6 may be entirely separate from the member 5, and in place of the hinge 9 a second detachable snap fastener, like 11, could be employed.

15 I claim as my invention:

1. In a device of the class described, the combination of two members of sheet material, one of said members being provided with oppositely arranged cut out portions, 20 and a wire rolled within the edge of said member and extending across said portions, spaced apertures in said member to receive the ends of a staple which are arranged to pass through apertures in a button and be 25 folded over upon said member, and a second member hinged to said wire at one of the cut out portions of the first-named member, and provided with a snap fastener to engage said wire opposite the other cut out portion 30 of said member, the second member being arranged to fold over upon the first-named member to conceal the ends of the wire staple.

2. In a device of the class described, the 35 combination of a member provided with a rolled rim having a strengthening wire therein, and with spaced apertures adapted to receive the ends of a button fastening

staple, said ends to be folded upon said member, of a second member hinged to an exposed part of the strengthening wire of said first-named member, and adapted to fold upon the latter, the second-named member being also provided with a snap fastener to engage another portion of said strengthening wire of the first-named member. 40 45

3. In a device of the class described, the combination of a member provided with apertures to receive the ends of a button securing staple, said ends being arranged to be folded down upon the face of said member, keepers to engage the staple ends at points beyond said apertures, and a second member hinged to the first member and arranged to fold thereover and conceal and 55 protect the ends of said staple.

4. In a device of the class described, the combination of a member provided with spaced apertures to receive the ends of a staple, tongues spaced from said apertures 60 and arranged to retain the staple ends in position on said member, a wire surrounding the edge of said member and resiliently seated therein, said wire having exposed portions located at opposite points on said member, and a second member hingedly connected to the first member by attachment to said wire at one of said exposed portions, and having a securing device arranged to engage the wire at the other of said exposed points, for maintaining said members in closed position. 65 70

In testimony whereof I have hereunto set my hand this 28th day of June, A. D. 1922.

JULIA A. ST. CLAIR.
